[57] CLAIM

The ornamental design for a pole charcoal grill, substantially as shown and described.

DESCRIPTION

FIG. 1 is a perspective view of a pole charcoal grill, showing my new design;

FIG. 2 is a side elevational view thereof, shown on a reduced scale;

FIG. 3 is a top plan view thereof;

FIG. 4 is a bottom plan view thereof;

FIG. 5 is a side elevational view thereof showing the side opposite that seen in FIG. 2;

FIG. 6 is a side elevational view thereof as seen from right to left of FIG. 5; and

FIG. 7 is a side elevational view thereof showing the side opposite that seen in FIG. 6.

FIG. 5

FIG. 6

FIG. 7
